UNITED STATES PATENT OFFICE.

JAMES FAZIO, OF VENICE, CALIFORNIA.

DESIGN FOR A CASING FOR A FRUIT CRUSHING, DISPLAYING, AND DISPENSING DEVICE.

Application filed December 12, 1923. Serial No. 8,003. Term of patent 7 years.

To all whom it may concern:

Be it known that I, JAMES FAZIO, a citizen of the United States, residing at Venice, in the county of Los Angeles and State of California, have invented a new, original, and ornamental Design for a Casing for a Fruit Crushing, Displaying, and Dispensing Device, of which the following is a specification.

As illustrated in the accompanying drawing, Fig. 1 is a perspective front view of the casing, showing my new design.

Fig. 2 is a side elevation of the device shown in Fig. 1.

I claim:

The ornamental design for a casing for a fruit crushing, displaying, and dispensing device, as shown.

In testimony that I claim the foregoing as my invention I have signed my name in the presence of two subscribing witnesses.

JAMES FAZIO.

Witnesses:

JOSEPH J. FAZIO,
E. HATTENBACH.
